Patented September 20, 1904.

UNITED STATES PATENT OFFICE.

AUGUST A. EHLMAN, OF COVINGTON, KENTUCKY.

DESIGN FOR A GRAVE-GUARD.

SPECIFICATION forming part of Design No. 37,151, dated September 20, 1904.

Application filed July 23, 1904. Serial No. 217,899. Term of patent 14 years.

To all whom it may concern:

Be it known that I, AUGUST A. EHLMAN, a citizen of the United States, residing at Covington, in the county of Kenton and State of Kentucky, have invented a new, original, and ornamental Design for Grave - Guards, of which the following is a specification, reference being had to the accompanying drawing, forming part hereof.

5 The accompanying drawing illustrates a per-

spective elevation of a new, original, and ornamental design embodying my invention.

I claim—

The ornamental design for a grave-guard, as shown.

AUGUST A. EHLMAN.
